UNITED STATES PATENT OFFICE.

CHARLES W. METCALFE, OF HOPKINSVILLE, KENTUCKY.

SCREW-PRESS.

SPECIFICATION forming part of Letters Patent No. 391,177, dated October 16, 1888.

Application filed March 26, 1883. Serial No. 268,475. (No model.)

To all whom it may concern:

Be it known that I, CHARLES W. METCALFE, a citizen of the United States, residing at Hopkinsville, in the county of Christian and State 5 of Kentucky, have invented certain new and useful Improvements in Screw-Presses; and I do declare the following to be a full, clear, and exact description of the invention, such as will enable others skilled in the art to which it 10 appertains to make and use the same, reference being had to the accompanying drawings, and to the letters and figures of reference marked thereon, which form a part of this specification.

15 This invention relates to improvements in machines for prizing tobacco, cotton, and other products, and my object is to facilitate the operation of using the press, especially when it is adapted for hand-power; also to dispense, 20 if desired, with the use of blocks between the head and follower.

To these ends the nature of my invention consists in the combination, with the master-screw of a press, of a segmental clamping device with a lever having an eccentric-head, as 25 will be fully understood from the following description and claims, taken in connection with the annexed drawings, in which—

Figure 1 is a perspective view of a hand- 30 press which has my improvements applied to it, representing one form of press to which my invention is applicable. Fig. 2 is an enlarged horizontal sectional view taken in the plane indicated by dotted line *x* on Fig. 1, showing 35 clearly three gripping-segments and the eccentric-head on the hand-lever. Fig. 3 is a top view of one of the gripping-segments having a tooth formed on its concave side, adapted to engage with the groove between the threads 40 of the master-screw. Fig. 4 is a radial section, indicated by dotted line *y* on Fig. 3, of one of the toothed gripping segments.

Referring to the annexed drawings by letter, A designates the horizontal base of a 45 press-frame, B the resisting-head thereof, and C four brace and tie bars securely uniting the said base and head, all forming a substantial structure which is adapted to resist great strain.

In Fig. 1 of the annexed drawings I represent 50 my invention applied to a hand-press which is especially designed for prizing to-

bacco, although I do not confine my invention to the pressing of this product.

G designates a hogshead supported temporarily upon the base A, and H designates a 55 step, which is centrally adjusted upon and may be permanently secured to a follower, H', which is free to lie upon the material being pressed, and which can be removed at pleasure from the hogshead during the operation of 60 pressing. When the screw D is sufficiently raised, it will leave the step H and allow the follower to be taken out of the hogshead.

The step H is adapted to receive freely the 65 lower end of a master-screw, D, the upper portion of which is tapped through a flanged nut, F, which is suitably secured into the head B of the press-frame. It will thus be observed that by rotating the screw D about its longest axis it will receive vertical movement.

I will now particularly describe my improved attachment to the above contrivance.

L designates a hand lever, which may be of any convenient length, and which is constructed with an enlarged head, L', having a segmental face, which is eccentric to a vertical fulcrum-pin, l, as indicated by the radial dotted lines *c c' c'* in Fig. 2.

R R designate two jaws, which are parallel to each other and in planes perpendicular to 80 the axis of the master-screw D. These jaws are held together by a bolt, a, its nuts and jam-nuts, and also by the bolt l, which latter is passed through the extensions r r of the said jaws, as clearly shown in Fig. 1.

N N N' designate three gripping-segments, which are shouldered at *n'* and fitted between the two jaws R R, so that they are more or less loose to be moved about the vertical axis of the screw D. Collectively the three segments N N N' do not form a complete circle, as shown in Fig. 2. The two segments N N have teeth or lugs *n* on their inner sides which engage with the thread of the screw D; but these teeth may be omitted, or in lieu thereof 95 the said two segments may have full female threads to engage with the said screw. The segment N' is threadless and is in close relation to the cam-shaped head L' of the hand-lever L, so that in the manipulation of this 100 lever—that is to say, whether it be forced toward the right or the left—the face of the cam

will be caused to impinge against the segment N', thereby forcibly pressing it against the screw D and causing the several segments to bind on it.

5 In combination with the above devices for clamping the screw I employ what I designate a "stop-pin," P. This pin is adapted to be received in either of the apertures s or the apertures s' through the extensions r of the 10 two jaws R R.

In the operation of the press, after the vessel G has been filled and the follower adjusted upon the material and centrally stepped beneath the screw D, the attendant adjusts the 15 stop-pin P in the apertures s'. He then vibrates lever L, and while moving this lever in the direction indicated by the arrows on Figs. 1 and 2 he causes the cam head of the lever to impinge on the segment N', thus gripping the 20 screw and causing it to descend. This operation is repeated until the material is pressed. The movements of the screw are reversed by changing the pin P to the holes s'. When lever P is adjusted in the position indicated in 25 Fig. 2, the cam will not impinge against the

segment N' and the screw D can be turned freely.

Having described my invention, what I claim as new, and desire to secure by Letters Patent, is—

30 1. The combination, in a press, with a master-screw provided with a pressing-head and a fixed nut, of a hand-lever having an eccentric head, jaw-plates to which this lever is pivoted, and gripping-segments applied to the 35 said jaw-plates adapted to be compressed about said screw by means of the eccentric on said lever, substantially as described.

2. The combination, with the press-screw, the lever having an eccentric head, the supporting-jaws, and gripping-segments, of a removable stop-pin, P, adapted to extensions of said jaws, substantially in the manner and for the purposes described.

In testimony whereof I affix my signature in 45 presence of two witnesses.

CHARLES W. METCALFE.
